UNITED STATES PATENT OFFICE.

ALBERT F. BEMIS, OF NEWTON, AND HORATIO W. BROWN, OF CONCORD, MASSACHUSETTS, ASSIGNEES, BY MESNE ASSIGNMENTS, TO BEMIS INDUSTRIES INC., OF BOSTON, MASSACHUSETTS, A CORPORATION OF DELAWARE.

CONCRETE BUILDING CONSTRUCTION.

Application filed February 17, 1922. Serial No. 537,178.

This invention relates to concrete building construction and more particularly to concrete houses and office buildings.

The objects of the invention are to facilitate and expedite the construction of such buildings, to economize the materials required in making such buildings, both in the materials forming a permanent part of the building and the materials employed as temporary supports in the construction of such buildings, to provide walls and floors having hollow interiors, to provide means interiorly of the walls to which the interior finish may be nailed or screwed, to provide maximum protection from the elements, to render the structures indestructible by fire or the elements, to provide attractive interior surfaces, and in general to improve the construction of buildings of the character referred to.

The invention can best be disclosed by reference to a specific construction, and one form of construction has therefore been shown in the accompanying drawings, in which,—

Fig. 1 is a perspective view from the exterior of the structure, showing parts broken away;

Fig. 2 is a similar view from the interior of the building, showing parts broken away; and

Fig. 3 is a perspective view of a wooden form employed in the construction.

The wooden form shown in Fig. 3 comprises side boards 1, end boards 2, one or more boards 3 intermediate the side boards 1, wooden laths 4 fastened at spaced intervals along one of the open sides of the form and furring strips 5 secured at wider intervals along the opposite open side of the form, the laths being intended to form a support for the interior plaster and the furring strips for the concrete on the opposite side. When these forms are used in the side walls of a building the furring strips are on the outside and the exterior concrete surface is applied thereover; and when the forms are used in floor construction the furring strips are on top and the concrete floor is applied thereover. Between the furring strips and the concrete wall or floor applied

thereover is provided a layer of impervious material such as burlap or tarred paper.

Referring to Figs. 1 and 2 the foundation is first formed up to the line 6. Forms F are then mounted in horizontal alignment, the outer ends of the forms being supported on the foundation 6 and the inner ends being supported on temporary supports, not shown. As shown in Fig. 2 the forms are mounted in spaced relationship leaving spaces 7 therebetween, these spaces being adapted to receive the concrete beams 8 of the floor. Before the concrete beams are molded in these spaces the bottoms of the spaces are closed by boards 9 and reinforcing rods 12 are placed in the spaces as shown in Fig. 2. It is important that the boards 9 extend wholly or partially into the spaces 7 so that the concrete beams do not entirely fill the spaces 7, whereby when the temporary boards 9 are removed after the beams have set a space is left between the lower sides of the beams and the plastering applied to the lower side of the forms. Such a space is shown at 10 in Fig. 2 and this space either may be an air space or it may be filled with an insulating material. Thus the concrete does not contact with the plaster and there is no danger of the plaster becoming stained by the concrete. Before the plaster is applied to the under side of the forms strips of wire mesh or metallic lathing 11 are applied over the bottoms of the spaces 7.

The beams 8 are molded simultaneously with the sills 13, a temporary form (not shown) being provided outside of sills 13. After the beams 8 and sills 13 have been poured the reinforcing mesh 14 is applied over the top of the forms, the impervious sheets of burlap or tar paper 15 having been previously applied over the furring strips 5. The concrete floor 16 is then formed. The beams and floor are preferably formed in a continuous operation so as to unite and form an integral body of concrete.

After the beams and floor have set, a temporary frame is erected upon the floor to which the forms of the walls of the first story and the floor of the second floor are attached while the concrete frame of the first story is being formed. This temporary

frame comprises base members 17 resting on the floor 16, upright studs 18 resting on the base members 17 at intervals and cap members 19 resting on the tops of the studs 18.

- 5 Blocks 20 are preferably interposed between the base members and the studs 18, the blocks 20 being nailed to the bottom of the studs before the studs are set up and the laterally extending portions of the blocks 10 being nailed to the base members 17 with double-headed nails whereby the studs can readily be detached from the base members in removing the temporary frame by merely pulling out the double headed nails which 15 secure the blocks to the base members.

In erecting the temporary frame the studs are preferably spaced at intervals slightly greater than the width of the forms F so that after the forms have been placed in position the studs will register with the spaces between the forms. The forms are set up in flatwise alignment with their lower ends resting directly upon the floor 16 and preferably with the spaces therebetween registering with the spaces between the floor forms so that the upright concrete supports subsequently molded in the spaces between the wall forms register with the floor beams. In setting up the wall forms the spaces therebetween are closed on the inside and outside by upright boards 21 and 22. The inside boards 21 preferably extend into the spaces to form air spaces as above described in connection with the floor construction. Cross pieces 23 are interposed between the studs and the inner faces of the forms and the outside board 22 overlies the adjacent forms so that when the outside boards are tied to the studs by wires 24 the forms are held in fixed position relative to the studs. The wires 24 may be tightened by pins 25 extending through loops in the outer ends of the wires, the wires being tightened by twisting the pins 25. The boards 21 and cross pieces 23 are preferably secured to the studs 18 before the studs are set up, these parts thus being set up as units.

The forms for the floor of the second story rest on the cap pieces 19 and extend outwardly over the wall forms as shown at 50 26 in Fig. 2. These floor forms not only overhang the wall forms but they are preferably spaced vertically somewhat above the tops of the wall forms, so that it is immaterial if the wall forms vary somewhat in height, the spaces between the tops of the wall forms and the floor forms being filled by concrete when the girder surmounting the wall forms is poured. After the floor 55 forms for the second story have been mounted the second floor is formed in substantially the same way as above described in connection with the first floor, an outside form board 27 being provided to confine the concrete forming the girder poured in the 60 65

space 28. The upright portions 29 of the concrete frame filling the spaces between the wall forms are poured at the same time as the second floor girders and beams. Additional stories may be erected in similar 70 manner.

After the concrete frame work has set sufficiently to be self-supporting, the temporary frame work may be removed. The pins 25 are removed from the wire loops 75 and the temporary outside boards 22 are removed. The temporary inside frame work is then removed.

Before the outside concrete surface 30 is applied the wire mesh reinforcing 32 for the 80 concrete is put in place, the ends of the wires 24 which encircle the pins 25 before the temporary structure was removed, serving to anchor the reinforcing 32 in place. The concrete surface 30 is then applied with a cement gun or by hand in the usual way.

Before the interior plaster surface 33 is applied strips of insulating material 34 are placed in the spaces formerly occupied by boards 21 and wire mesh 35 is applied over 90 these strips. The plaster surface 33 may then be applied in the usual way. By virtue of the wooden forms embedded in the walls, the interior finish may be readily attached by means of nails or screws as in a wooden 95 building.

We claim:

1. A concrete structure comprising monolithic outer walls having integral studs, and permanent unitary forms embedded in said walls and each providing plaster supporting elements lying in a plane spaced from the plane of the inner surface of said studs and terminating adjacent said studs, said elements being aligned with similar elements upon adjoining forms.

2. A concrete structure comprising monolithic side walls and floors, said walls and floors having hollow forms permanently embedded therein, studs and beams integral 110 with said walls and floors respectively, and plaster supporting means carried by said forms and so constructed and arranged as to support plaster mounted thereon in spaced relation to adjacent studs or beams.

3. A concrete building comprising a plurality of spaced, permanent forms providing a support for a slab of concrete, a supporting rib of concrete integral with said slab and arranged between said forms, a 115 sheet of plaster spaced from said concrete and carried by said forms, and insulating means interposed between said plaster and the adjacent surface of said rib.

4. A floor construction comprising a plurality of spaced frames of shallow box-like construction, said frames each having furring strips extending across their open upper sides and laths extending across their lower sides, wire mesh extending across the 125 130 135

spaces between said frames on the lower side, and a sheet of imperforate material secured to the furring strips of each frame and serving to close the spaces between said strips.

5. The method of making a concrete building construction which comprises erecting in spaced relationship separate unitary wall forms of substantially the height of a story and having plaster supporting elements upon one side thereof, mounting in spaced relationship separate unitary floor forms with plaster supporting elements upon their lower sides at approximately the level of the upper ends of said wall forms, bridging the spaces between said forms with temporary closures, forming in said spaces the vertical and horizontal elements of the concrete frame structure, removing said temporary closures to leave the wall forms and floor forms respectively joined together only by the concrete structure, and inserting plaster receiving means between aligned plaster receiving elements upon the forms, and applying plaster to the aligned surfaces thus provided.

6. The method of making a concrete building construction which comprises erecting in spaced relationship separate unitary wall forms of substantially the height of a story and having plaster receiving elements upon one side thereof, mounting in spaced relationship separate unitary floor forms with plaster receiving elements upon the lower side thereof at approximately the level of the upper ends of said wall forms, bridging the spaces between said forms with temporary closures, forming in said spaces the vertical and horizontal elements of the concrete frame structure, allowing said concrete to set, and applying a continuous layer of plaster to the aligned plaster receiving elements of the forms.

7. The method of making a concrete

building which comprises erecting in spaced relationship separate unitary wall forms of substantially the height of a story and having means for the application of plaster upon at least one side, mounting in spaced relationship separate unitary floor forms at approximately the level of the upper ends of the wall forms, said forms having plaster supporting means at their lower sides, bridging the spaces between said forms with temporary closures, forming in said spaces the vertical and horizontal elements of the concrete frame structure to such an extent that the planes of the plaster receiving means are in planes spaced from said elements, bridging the spaces thus formed with plaster receiving elements the planes of which are aligned with the plaster receiving means, applying plaster to the surfaces thus afforded to provide a monolithic building construction with plaster supported in spaced relation to the concrete elements.

8. The method of making a concrete building which comprises erecting in spaced relationship separate unitary wall forms of substantially the height of a story and having means for the application of plaster upon at least one side, bridging the spaces between said forms with temporary closures, forming in said spaces the vertical elements of the concrete frame structure, to such an extent that the planes of the plaster receiving means are spaced from said elements, bridging the spaces thus formed with plaster receiving elements the planes of which are aligned with the plaster receiving means, applying plaster to the aligned surfaces thus afforded to provide a monolithic building construction with plaster supported in spaced relation to the concrete elements.

Signed by us at Boston, Massachusetts, 85
